UNITED STATES PATENT OFFICE

EARL W. NORTHCROFT AND JAMES IRONSIDE, OF DETROIT, MICHIGAN, ASSIGNEES, BY
MESNE ASSIGNMENTS, TO CLAYTON & LAMBERT MANUFACTURING CO., OF DETROIT,
MICHIGAN, A CORPORATION OF DELAWARE

STAND STRUCTURE

Application filed August 21, 1926. Serial No. 130,574.

Our invention relates to stand structure and has to do with the provision of a novel stand structure of the collapsible type and has many advantages both as to stability 5 and production cost.

One of the objects of our invention is the provision of a main unit and auxiliary unit which are both specially constructed with relation to each other in order that the auxiliary unit be effectively reinforced by the main unit whenever such main unit is utilized. In this respect the stand is applicable to present supporting surfaces of two or more heights and to increase the rigidity of the 15 general structure as the height of the supporting surface is increased.

Another object of our invention consists in the provision of a stand structure having two sets of supporting legs and the arrangement 20 of such legs whereby the one set forms directly the reinforcing means for the other set without the interposition of any connecting bolts or lugs.

A further feature of our invention has to 25 do with a novel collapsible shelf section which forms a collapsible part of the stand and, which due to this peculiar structure, serves to lock the stand in extended position and also serves to support itself.

A still further feature of our invention relates to the collapsible leg section, the manner 30 of collapsing same and the novel results derived from the various positions of the collapsible parts both when collapsed and when 35 extended.

In the drawings:

Fig. 1 is a perspective view of a collapsible stand embodying the features of our invention and particularly illustrating the 40 use of the auxiliary legs as reinforcing members for the main legs.

Fig. 2 is an enlarged detail view taken on line 2—2 of Fig. 1 and illustrating the novel locking nut which serves as the sole pivot for 45 the auxiliary legs which also serves to lock the legs in collapsed and extended position.

Fig. 3 is a perspective view showing supporting of the stand in its lower position by means of auxiliary legs and also illustrating 50 the manner of collapsing the main legs and

the supporting shelf whereby the supporting shelf in a measure forms a top for the stand.

Fig. 4 is an enlarged detail sectional view taken on line 4—4 of Fig. 3 and illustrating the position of the various parts when in 55 collapsed position whereby a large amount of friction is obtained to maintain such collapsed parts in position.

Fig. 5 is a fragmentary perspective view of our auxiliary stand unit and showing in 60 particular the construction of the auxiliary leg and the manner of hinging it to the top frame structure of the stand.

Fig. 6 is a bottom plan view of the stand in collapsed position.

Fig. 7 is an enlarged fragmentary sectional view taken on line 7—7 of Fig. 1, and illustrating the manner of locking the main legs and the stand in general in extended 70 position.

Fig. 8 is a diagrammatical view illustrating the manner of positioning the stand preparatory to collapsing or extending the same.

Fig. 9 is a diagrammatical view similar to 75 Fig. 8 showing the locking lugs compressed for the collapsing or extending of the auxiliary supporting means.

Fig. 10 is a fragmentary perspective view, partly broken away, and illustrating the manner of folding the main legs longitudinally of 80 the stand and the auxiliary legs transversely thereof.

In the drawings our collapsible stand construction is shown as comprising a light but 85 sufficiently strong inner main unit together with an outer auxiliary unit. These inner and outer units are so built that they will serve as complements to each other for the purpose of rigidly, compactly reinforcing and supporting the stand structure.

Referring particularly to Fig. 1, it will be understood that the inner main unit structure is made up of the leg member sections 1 and 2, the two legs at each end forming 95 the leg member sections 1 and 2 which are provided with suitable cross braces 3. These leg members 1 and 2 are preferably formed of relatively light angles. The leg sections are pivotally connected at their upper end, 100

as at 4, to the top frame member 5 which is preferably rectangular in shape and angular in cross section. Pivots 4 for connecting the legs of the main unit to the stand frame are 5 preferably positioned at a distance from the ends of the frame 5, as best illustrated in Figs. 5 and 10.

The main leg sections 1 and 2, connected by the braces 3 may be of any desired length 10 corresponding to the length of the stand whereby the legs may be folded within the length of the stand. Such leg sections, being angular in cross section, are so positioned that when folded inwardly and longitudinally 15 about the pivots 4 they will fold together with the sides of the angles parallel, as shown in Fig. 4.

This inner main unit, consisting of the leg sections 1 and 2, is reinforced by an outer 20 auxiliary unit which comprises the oppositely disposed leg sections 6 and 7, pivotally connected to the frame 5, said leg sections being connected by a flexible brace 8. The ends of the frame 5 are provided with squared apertures 9 and 10 at each end thereof, and such apertures are designed to receive novel studs 11 which are so formed as to be square in cross section for a part of their length and round in section for a part of their length. 25 The axes of the studs 11 are positioned at right angles to the axes of the pivots 4, and such studs 11 form the sole pivots for pivoting the leg sections 6 and 7 to the frame 5.

The auxiliary leg sections which comprise 30 the two legs 6 and 7 and the connecting bars 8 are adapted to be assembled with relation to frame 5 by flexing the bars 8 whereby the studs 11 at the ends thereof may be quickly dropped into place into the square apertures 9 and 10 at each end of the frame 5. It will be obvious that the flexible leg sections comprising the short legs and the flexible connecting means may be disassembled in the same manner, but the main novel result in 45 this construction resides in the ease of assembly, because when once assembled the stand need not, under ordinary conditions, be disassembled. The squared portions of the studs 11 are adapted to cooperate with 50 the squared apertures 9 and 10 when the leg sections 6 and 7 are in either extended or collapsed position; that is, either at right angles or parallel with the frame member 5 and such studs 11 are designed to be 55 silently held in either one of said locking positions by means of the spring clips 12 which are preferably riveted to the auxiliary leg members, as shown in Figs. 5 and 10.

It will therefore be obvious that in order 60 to collapse or extend the auxiliary leg members 6 and 7 that it will only be necessary to press inwardly on the studs 11 whereby the squared portions of the studs are disengaged from the square apertures and the leg sections will be free to move transversely of

the stand about the rounded portions of the studs 11. The positioning of the spring pressed studs 11 at the corners and each end of the frame 5 has a definite purpose in that such positioning makes it possible to very easily collapse or extend the auxiliary legs 6 and 7 and incidentally the entire stand. In other words, as best illustrated in Figs. 8 and 9, the studs 11 may be actuated and the stand collapsed or extended by merely placing one end of the frame 5 against the floor or other suitable surface and then pressing against the studs at the opposite end, as shown in Fig. 9, whereby the pressing inwardly of the two upwardly projecting studs will simultaneously compress the two downwardly projecting studs which contact with the floor. This thus presses upon the studs inwardly and makes it possible to quickly and easily move the leg members 6 and 7 towards the desired position.

The short legs of the auxiliary leg members 6 and 7 are angular in shape similar to the main legs and are so pivoted about the studs 11 as to fit squarely within the corners formed by the frame 5, when such leg members are in extended position. Thus the pivoting of the short legs about the pivots 11 and the positioning of the same serves to reinforce the legs against pressure in one direction while the connecting bars 8 serve to reinforce the legs against pressure in the other direction. As the longer legs are pivoted to move longitudinally of the stand and the shorter legs are positioned on the outside thereof and pivoted to move transversely of the stand, it will be obvious that the main stress on the main legs will be in a direction longitudinally of the stand, and the shorter legs are positioned on the outside thereof and pivoted to move transversely of the stand, it will be obvious that the main stress on the main legs will be in a direction longitudinally of the stand, and this main stress will be counteracted and such main legs rigidly reinforced by the auxiliary legs which are reinforced by the bars 8 and which are positioned when extended at an angle to the main legs. This pivoting of the main legs about the pivots 4, which are so positioned as to cause the main legs to extend downwardly and outwardly, when extended, is one of the main features of our invention, as it will be obvious that when the units and the leg sections thereof are extended that the more pressure brought to bear upon the top of the stand that the greater will be the reinforcing action of the auxiliary legs. This novel reinforcing is the result of the pivoting of the leg members of the two units, the reinforcing of the auxiliary leg members and the complementary positioning of the leg sections of the two units.

The stand will be sufficiently rigid when utilizing either the main unit or the auxiliary unit, but we have added an additional feature

which not only reinforces the stand but which adds to its usefulness as a stand in that we have provided a collapsible shelf member which is preferably formed in two parts which may be designated 13 and 14. These two sections which form the shelf are preferably of pressed corrugated sheet metal, the corrugations and turned down edges of each section interfitting in complementary relation. The shorter shelf member 13 is pivoted to the main leg section 1 preferably just inside the brace 3, and the longer shelf section 14 is pivoted to the shorter section 13 at a point 15. The opposite end of the entire shelf unit, and particularly the end of the section 14 is turned down, as at 16, see Fig. 7, and the corners formed by the meeting of the turned down edge 16, and the longitudinal turned down edges of the shelf are cut away, as at 17, whereby the shelf section 14 when extended fits in locking position with reference to the brace member 3, connecting the main legs of the leg section 2. In other words, the cut away portion 17 makes it possible to position the turned down edge 16 on the outside of the brace 3 and the end of the turned down portions at the side of the shelf on the inside of the brace 3 thereby locking the leg section 2 against movement in either direction and incidentally locking the entire table as when the two sections 13 and 14 of the shelf are extended, as shown in Fig. 1, the overlapped portions caused by the pivoting of the section 14, as at 15, produces a cantilever action which rigidly holds the main leg sections in extended position, and preferably in contact with the auxiliary legs 6, and which cantilever action also reinforces the center of the shelf making it unnecessary otherwise to support the shelf in the center.

40 Thus by the mere addition of a shelf member which is collapsible and has great utility, we have provided means of positively locking the main leg sections in extended position and for giving the stand the greatest possible rigidity with a minimum amount of material.

45 In collapsing the stand from the position shown in Fig. 4 it is only necessary to raise the end of the shelf section 14 to disengage the same from the brace 3 and then raise the shelf unit in the center or about pivot 15. The two shelf sections then fold flatly together in parallel relation and also fold initially against and within the angles formed by the leg section 1, this is clearly shown in Fig. 4. The leg section 1, together with the folded shelf sections 13 and 14, may then be folded inwardly and longitudinally upwardly against and within the angles formed by the frame member 5. Having folded the leg sections 1 and the shelf sections 13 and 14 within the frame member, as shown in Fig. 4, the leg section 2 is then folded inwardly and upwardly into a space between the one angle of the leg section 1 and the downwardly

extending leg of the angle formed by the frame 5. When completely collapsed these sections show a cross section, as illustrated in Fig. 4, whereby five layers of sheet metal are packed closely together. These various angles, as shown in Fig. 4, are preferably so positioned, that when so collapsed they contact with each other with a certain amount of friction whereby the shelf units and the main leg sections are frictionally maintained in such collapsed position. In fact, this friction is so great that when the table is partially collapsed, as shown in Fig. 3, whereby only the auxiliary unit is utilized, the collapsed shelf sections serve as a table top and cannot be normally pressed downwardly except by separately disengaging the main leg sections beneath the shelf sections. This serves an important purpose in that when the frame member 5 is hollow, or annular, as shown, that an ordinary table may be provided when the short table is used. The main leg sections and shelf having been once collapsed, as shown in Fig. 3, it is only necessary to actuate the studs 11 whereby the auxiliary leg sections 6 and 7 may be folded inwardly and retained in locking position by the contacting of the squared bolts of the studs with the squared apertures 9 and 10.

45 The top of the table, or the frame 5, is preferably hollow, or annular, as shown, whereby any suitable receptacle or unit, such as a camp stove or other article, may be fitted therein, that is, such article may be struck up or recessed so that the struck up portion may project downwardly and fit within the frame 5.

50 The size of the angle members forming the various legs, and the frame 5 are such that when all the leg members, including the leg sections 1 and 2, 6 and 7 and the shelf sections 13 and 14 are folded in position as shown in Fig. 6, all of such folded parts are positioned within the plane of the frame 5. In other words, all of the parts of this collapsible two-stage stand fold flat and collapse into a unit which is of no greater width than the width of the angle member forming the frame 5.

55 In extending the stand from collapsed position it is only necessary to actuate the studs 11, as illustrated in Fig. 9, and then progressively unfold the auxiliary leg sections to locked position, then the main leg sections, and then the shelf sections 13 and 14.

60 What we claim is:

1. A collapsible stand structure comprising a collapsible inner unit and an outer unit each arranged to independently support a stand at different heights, and means connecting the two units whereby the one unit reinforces the other when in extended position.

65 2. A collapsible stand structure comprising a collapsible inner unit and an outer unit

each arranged to independently support a stand at different heights, and means connecting the two units whereby the outer unit reinforces the inner unit when in extended position.

3. A collapsible stand structure adapted to be positioned to a plurality of heights, comprising an outer unit independently adapted to position and support the stand at one height, and an inner unit independently adapted to support and position the stand at another height, and means connecting the two units whereby said inner unit and outer unit are complementally positioned and arranged when extended to reinforce each other.

4. A collapsible stand structure comprising leg sections and single means serving as pivots and positive locking means for connecting the leg sections to the stand structure in either 20 rotative or locked relation.

5. A collapsible stand structure comprising a frame, leg sections pivoted to and foldable with relation to said frame and locking means including a spring-pressed stud positioned at each end of the frame and adapted to be simultaneously actuated to release by positioning one end of the frame against the floor for permitting collapsing or extending of said leg sections, said leg sections being 30 foldable with relation to the frame only upon simultaneous actuating of the locking means.

6. A collapsible stand structure comprising a leg section foldable transversely of the stand, and a second leg section foldable longitudinally of the stand, and means for positioning said leg sections complementally in overlapped relation when in extended position whereby they are mutually reinforcing.

7. A collapsible stand structure comprising 40 a main unit and an auxiliary unit, said main unit having leg sections foldable longitudinally of the stand and said auxiliary unit having leg sections foldable transversely thereof said sections interfitting when in extended position to be reinforced by each other.

8. A collapsible stand structure comprising a supporting frame, a supporting leg therefor freely pivoted to the frame and another leg member also pivoted to the frame at 50 a point positioned from said first named pivot whereby said first named leg member contacts with said second named leg member and at an angle thereto whereby one of said leg members reinforces the other.

55 9. A collapsible stand structure comprising inner and outer leg sections, a frame, one of said leg sections being freely and pivotally mounted on said frame and the other leg section being also pivotally mounted to the frame, identical means for both pivoting and automatically locking said last named leg section in collapsed position.

10. A collapsible stand structure comprising inner and outer leg sections, a frame, one 60 of said leg sections being freely and pivotally

mounted on said frame, the other leg section being also pivotally mounted to the frame, and identical means for pivoting and automatically locking said last named leg section in collapsed or extended position.

70 11. A collapsible stand structure comprising a frame member and foldable leg sections for supporting the frame member, said leg sections each comprising two legs connected by a flexible brace whereby the brace may be flexed and the leg section assembled into 75 position as a unit.

75 12. A collapsible stand structure comprising a frame member and apertures in said frame member for receiving bearing studs, 80 said bearing studs forming the sole connecting means between leg sections and said frame member, and flexible means for connecting two legs of the leg section whereby said means may be flexed to assemble said leg section as 85 a unit.

85 13. A collapsible stand structure comprising inner and outer supporting units, said inner unit formed by leg sections comprising two legs joined by a reinforcing member positioned transversely of the stand and said outer unit made up of leg sections formed of two legs joined by reinforcing members positioned longitudinally of the stand, said inner and outer units being foldable in overlapped relation.

90 14. A collapsible stand structure comprising a plurality of independent collapsible units adapted to be extended to support the stand at different heights, one of said units being foldable within the other when not being utilized as a support, the parts of said folded unit contacting with each other with sufficient friction to maintain the folded unit in collapsed position.

95 15. A collapsible stand structure comprising an inner and outer unit, the legs of one unit being positioned at an angle to the legs of the other unit whereby the legs of one unit reinforces those of the other, the legs of one unit being collapsible to permit the legs of the other unit to support the stand at a different height.

100 16. A collapsible stand structure comprising two units, one made up of relatively short legs, and the other of relatively long legs and a collapsible shelf structure for reinforcing the long legs, said shelf consisting of a plurality of pivotally connected overlapping parts.

105 17. A collapsible stand structure comprising two units, one unit made up of relatively short legs, and the other of relatively long legs, said short legs being positioned to reinforce the long legs and a collapsible shelf member for reinforcing the long legs, said shelf member consisting of a plurality of pivotally joined parts.

110 18. A collapsible stand structure comprising a main unit and auxiliary unit formed

of relatively light weight angles, the legs of said auxiliary unit being positioned to reinforce the legs of the main unit, and a relatively thin collapsible corrugated shelf member for reinforcing the main unit.

19. A collapsible stand structure comprising a main unit and auxiliary unit formed of relatively light weight angles, the legs of said auxiliary unit being positioned to reinforce the legs of the main unit, and a relatively thin collapsible corrugated shelf member for reinforcing the main unit, the parts of said shelf structure being joined to present a cantilever action when extended to reinforcing position.

20. A collapsible stand structure comprising collapsible leg members and a collapsible shelf member adapted to be connected to and to reinforce the legs when extended, the sections of said shelf member being connected to provide a cantilever action whereby said shelf is self supporting.

21. A collapsible stand structure comprising a top frame member and a plurality of independent units for supporting the stand at different heights, one of said units being foldable within the other and both of said units being foldable within said frame member, the legs of one of said units being automatically locked when collapsed to lock the entire structure in collapsed position.

22. A collapsible stand structure comprising inner and outer units, said inner unit comprising relatively long legs and said outer unit comprising relatively short legs, a frame for carrying said inner and outer units, the legs of said outer unit being adapted to be reinforced by the legs of said inner unit and a collapsible shelf member adapted to reinforce said inner unit, all of said elements being collapsible and foldable within the plane of said frame.

23. A collapsible stand structure comprising a frame, a leg foldable with relation to the frame, and a single member connecting the frame and the leg, the said member arranged in one position to lock the frame and the leg and in another position to pivotally connect the frame and the leg.

24. A collapsible stand structure comprising a frame, a plurality of independently collapsible leg units adapted to be extended to support the frame at different heights, one of said units being foldable within the other when not being utilized as a support, the said folded unit engaging the frame with sufficient friction to maintain the folded unit in collapsed position.

In testimony whereof we affix our signatures.

JAMES IRONSIDE.
EARL W. NORTHROP.
